UNITED STATES PATENT OFFICE.

JAMES F. CRAVEN, OF PITTSBURG, PENNSYLVANIA.

SECTIONAL SHEET-METAL WHEEL.

No. 928,633.

Specification of Letters Patent.

Patented July 20, 1909.

Application filed January 15, 1909. Serial No. 472,459.

To all whom it may concern:

Be it known that I, JAMES F. CRAVEN, a resident of Pittsburg, in the county of Allegheny and State of Pennsylvania, have invented a new and useful Improvement in Sectional Sheet-Metal Wheels, of which the following is a specification.

This invention relates to sectional or split wheels and more particularly to such wheels constructed of sheet metal.

The object of the invention is to provide split wheels, such as pulleys, vehicle wheels or the like formed of sheet metal to insure lightness and which are strong and can be cheaply and accurately formed.

The invention comprises a wheel constructed as hereinafter described and claimed.

In the accompanying drawings Figure 1 is in part a side view and in part a section transverse to the axis of a pulley embodying the invention; Fig. 2 is a section taken on the line 2--2, Fig. 1; Fig. 3 is a face view of the rim where the two sections come together; Fig. 4 is a perspective view showing the interlocking at the ends of the rim sections; Fig. 5 is a cross section through one of the spokes on the line 5--5, Fig. 1; Fig. 6 is a perspective view of a portion of one of the split spokes; and Fig. 7 shows one of the yokes for securing the members at the hub.

In the drawings the invention has been shown embodied in a sectional or split pulley and the invention will be described in connection with the same, but it will be understood that it applies to a wheel of any character formed of sheet metal.

The pulley shown comprises two equal semi-circular sections. Each of these sections is formed of two or three main portions or members, the drawings showing three, namely, a rim member 1, and two body or spider members 2 and 3. For very light pulleys the rim member may be omitted. The body members 2 and 3 are similar and formed from sheet metal and are practically of semi-circular shape. Each comprises a semi-annular central or hub portion 4 having its edges turned outwardly to form practically a tubular hub, a semi-annular rim portion 6 whose edges are turned or flared outwardly as shown in Fig. 2, and the radial spoke portions 7 extending from the hub portion 6 and forming the union between the same. These body members are pressed to the desired shape in dies and the two are then

placed back to back and suitably secured together. This union may be effected in any suitable way, but preferably as shown in the drawings, namely, by crimping or folding together the edges of the sheets around the openings or holes 9 bounded by the spokes hub and rim portions. The holes in one of these members are somewhat smaller than the holes in the other member, so as to leave a portion of metal 10 on the one member extending beyond the edge of the metal on the other member, said extended portion being then lapped around and over the edge of the member having the larger hole so as to form the crimped, folded or interlocked joint as shown at 11, Fig. 5. This folded or crimped joint extends entirely around each opening 9, except at the spokes where the two sections come together as is apparent from Fig. 1.

Preferably the extended locking portions 10 at the edges around the openings 9 are formed alternately on the two members so that the metal on one edge of a spoke is folded in one direction and that on the opposite edge of the spoke is folded in the opposite direction. This insures balancing of the stresses and gives a truer pulley, although it is not absolutely necessary.

By the means described the two body members 2 and 3 are rigidly united to form substantially tubular spokes with locked seams, thereby securing great strength for the weight of metal employed.

The two sections of the pulley are joined, or as it might be otherwise described, the pulley is divided through two of the oppositely arranged spokes, the said spokes being divided in a plane transverse to the axis of the pulley. The consequence is that the spoke member 13 on one face of the pulley is a part of one section of the pulley, namely, a part of the body portion 2, while the member 14 of the same spoke (see Fig. 2) is a part of the body member 3 of the other section of the pulley. In other words, in each half of the pulley the body member 2 is provided with a spoke member 13 on one of its radial edges, while the other body member 3 of the same half of the pulley is provided with a similar spoke member 13 arranged diametrically opposite to the spoke member on the body member 2, but facing in the opposite direction. The spoke members 13 and 14 lie beyond the radial edge portions of the companion body member 3 or 2 as the case

- may be and also lie on opposite sides of a plane transverse to the axis of the pulley and in the median line of the rim face of the same, as will be readily understood from the drawings. The two halves of the pulley are united by means of bolts or the like 15 extending through the spoke members 13 and 14. At the point where these bolts extend through the spokes the metal around the 10 holes is turned inwardly to form tubular projections 16 which abut and serve as spacing members. Separate spacing members may be employed if desired. The edges of the 15 spoke members 13 and 14 are obviously not crimped together, as this would prevent separation of the pulley, but they are provided with slight edge flanges 17 against which the edge of the companion member abuts, thus preventing relative movements of the pulley 20 sections transversely of the axis of the pulley. An interlock against radial movement is secured by providing each spoke member with an edge projection 18 entering a corresponding cut away portion 19 in the flange 25 17 of the companion spoke member.
- The rim 1 will be varied according to the character of wheel to be formed. For light wheels the peripheral portions 6 may be turned outwardly to form the wheel face. 30 For heavier pulleys as shown in the drawings the rim is a thin plate having its edges secured to the edges of the body or spider portion, preferably by beading. The outwardly flaring peripheral edges of the body 35 members are first beaded, as shown at 20, and the edges of the rim member are then beaded over the same, as at 21, thus giving a very rigid and strong construction. If desired a strengthening wire 22 may be and 40 preferably is inclosed in the bead.
- The ends of the rim members are of the form shown in Figs. 3 and 4, that is to say, the line dividing the two rim members instead of being a straight line transverse of 45 the rim is staggered or zigzag, having two transverse lines 25 and 26 not in line with each other, and a longitudinal line 27 joining the two transverse lines, the line 27 being in the same plane as the meeting faces of the 50 two spoke members 13 and 14, one of which is joined to the projecting part 29 of one rim member and the other to the projecting part 30 of the other rim member. Preferably the metal at the edges of the projecting parts 29 55 and 30 is flanged so as to lie practically radially in the pulley, as shown at 31 in Fig. 4, and giving a better bearing than would be afforded by the edges of the thin sheet metal abutting directly.
- 60 The hub construction can be of any suitable kind. For very light work the sheet metal hub can be directly clamped to the shaft. Preferably, however, a casting of other solid semi-tubular hub or bushing member 35 will be placed inside of the tubu-

lar hub portion, said members preferably having projections 36 entering the inner ends of the tubular spokes. Any suitable clamping means may be used, the drawings showing a well known type of clamp comprising 70 yoke members 37 fitting over the ends of the semi-tubular hub portions and united by means of compression bolts 38.

The construction described provides a pulley or other wheel of very light construction 75 and one which can be cheaply and accurately formed and possessing great strength for its weight. The entire wheel is formed of four or six main members, namely, for heavy wheels two rim members which are duplicates of each other and four body members which are practically duplicates except for the difference in the construction of the spoke members 13 and 14, and the fact that in one of said body members this spoke member is on one edge and on the other body member it is on the opposite edge. It will therefore require but two sets of dies for making the body members.

All of the operations in the construction of 90 the pulley can be performed by suitable sheet metal working apparatus, such as dies and beading rolls and according to methods which are well understood. The operations can be quickly performed so that the labor 95 cost is low and the light weight of the metal brings the cost of material down to a low figure. Since practically all of the work is die work a true wheel is insured.

What I claim is:

1. A sectional metal wheel comprising hub and rim members and spokes uniting the same, said wheel being divided through the rim and hub on a plane parallel to the axis of the wheel and through oppositely arranged 105 spokes on a plane transverse to the axis of the wheel, the members of the divided spokes being provided with edge flanges.

2. A sectional metal wheel comprising hub and rim members and spokes uniting the 110 same, said wheel being divided through the rim and hub on a plane parallel to the axis of the wheel and through oppositely arranged spokes on a plane transverse to the axis of the wheel, the meeting faces of the divided 115 spokes interlocking against movement radially to the axis of the wheel.

3. A sectional metal wheel comprising hub and rim members and spokes uniting the 120 same, said wheel being divided through the rim and hub on a plane parallel to the axis of the wheel and through oppositely arranged spokes on a plane transverse to the axis of the wheel, the meeting faces of the divided 125 spokes being provided with co-operating projections and depressions to interlock the same against movement radially of the axis of the wheel.

4. A sectional metal wheel comprising hub and rim members and spokes uniting the 130

same, said wheel being divided through the rim and hub substantially parallel to the axis of the wheel and through oppositely arranged spokes on a plane transverse to the axis of the wheel, said spokes being hollow with one half thereof fitting against a flange on the other half.

5. A sectional metal wheel comprising rim and hub members and spokes uniting the same, said wheel being divided through oppositely arranged spokes on a plane transverse to the axis of the wheel and through the rim on a staggered line.

6. A sectional metal wheel comprising hub and rim members and spokes uniting the same, said wheel being divided through oppositely arranged spokes on a plane transverse to the axis of the wheel and through the rim on a longitudinal line in the plane dividing the oppositely arranged spokes and on two transverse lines joining the ends of said longitudinal line.

7. A sectional metal wheel comprising hub and rim members and spokes uniting the same, said wheel being divided through oppositely disposed spokes on a plane transverse to the axis of the wheel and through the rim on a longitudinal line in the plane dividing the oppositely disposed spokes and on two transverse lines extending from the ends of the longitudinal line to the edges of the rim, the meeting faces of the divided spokes interlocking.

8. A sectional sheet metal wheel having each section composed of two members each cut out to provide hub and peripheral portions and radial spoke portions, said members being suitably united and each section having on one radial edge a half spoke on one of said members and on the other radial edge a half spoke on the other member.

9. A sectional sheet metal wheel having each section composed of two sheet metal members each cut out to provide hub and peripheral portions and radial spoke portions, said members being suitably united and each section having on one radial edge a half spoke formed on one of said members and on the other radial edge a half spoke formed on the other of said members, said half spokes lying

on opposite sides of the median plane of the wheel transverse to its axis.

10. A sectional sheet metal wheel having each section composed of two sheet metal members, each cut out to provide hub and peripheral portions and radial spoke portions, said members being united by folding together their edges around the openings between hub, rim and spokes, and having on one radial edge a half spoke formed on one of said members and on the other radial edge a half spoke formed on the other of said members.

11. A sectional sheet metal wheel having each section composed of two sheet metal members each cut out to provide hub and peripheral portions and radial spoke portions, said members being united by folding together their edge portions around the openings between hub, rim and spokes, and each section having on one radial edge a half spoke formed on one member and on the other radial edge a half spoke formed on the other member, said half spokes lying on opposite sides of the median plane of the wheel transverse to its axis.

12. A sectional sheet metal wheel comprising hub and rim members and tubular spokes integral with the hub and rim members, said wheel being divided through the rim and hub on a plane substantially parallel to the axis of the wheel and through oppositely disposed spokes on a plane transverse to the axis of the wheel.

13. A sectional sheet metal wheel comprising hub and rim members and tubular spokes uniting the rim and hub members and provided with locked seams, said wheel being divided through the rim and hub on a plane substantially parallel to the axis of the wheel and through oppositely disposed spokes on a plane transverse to the axis of the wheel, and interlocking means on the meeting faces of said sections.

In testimony whereof, I have hereunto set my hand.

JAMES F. CRAVEN.
